GAME

Herbert W. Harris, Racine, Wis.

Application December 22, 1941, Serial No. 423,973

2 Claims. (Cl. 273—110)

This invention appertains to games and game apparatus, and more particularly to game machines of the type commonly referred to as pinball machines.

One of the primary objects of my invention is to provide a pinball machine which will afford a maximum amount of amusement and interest to the players and onlookers, and one which is easily understood and played, but yet requires great skill and a steady hand to obtain a satisfactory high score.

In all pinball machines with which I am familiar, the element of chance in making a high score is paramount. The skill of the player enters very little into the game, and the player loses control over the movement of the ball as soon as the ball is projected onto the game board.

Therefore, another salient object of my invention is to provide novel means, first, to project the balls at different speeds or force from the ejecting mechanism; second, to control the path of the balls as the same are ejected; and, third, to control the path of the balls (within certain limits) on the game board after the balls have been shot.

Another important object of my invention is the provision of a game embodying a game board having a series of tracks arranged at different levels, with means simulating a pistol for projecting balls one at a time with selected force or power through the center of the board to cause the balls to travel from one track to the other, means being provided for scoring points as the balls move over the tracks.

A further object of my invention is the provision of means for mounting the ejecting pistol and the game board together in such a manner and within the cabinet of the machine that the pistol and game board can be tilted in any direction, whereby the line of travel of the ball projected can be controlled by the player, and whereby the board can be tilted by the player to control the travel of the ball from one track to another on the game board.

A further important object of my invention is the provision of means under the control of the operator for compressing the projecting spring to any selected point and then quickly releasing the projecting mechanism to project the balls with the desired speed or force.

A still further object of my invention is to provide means whereby the game can be simplified to a great extent to permit the same to be used as a handball game.

With these and other objects in view, the invention consists in the novel construction, arrangement, and formation of parts, as will be hereinafter more specifically described, claimed, and illustrated in the accompanying drawings, in which drawings:

Figure 1 is a perspective view illustrating one form of pinball machine embodying the principles of my novel game.

Figure 2 is an enlarged, fragmentary, central, vertical section through the machine.

Figure 3 is a horizontal sectional view through the machine, taken on the line 3—3 of Figure 2, looking in the direction of the arrows.

Figure 4 is a top plan view of one form of game board, which can be used in the pinball machine.

Figure 5 is an enlarged, transverse, sectional view taken on the line 5—5 of Figure 2, looking in the direction of the arrows, illustrating the latch release mechanism for the projecting plunger.

Figure 6 is an enlarged, detail, sectional view taken on the line 6—6 of Figure 2, looking in the direction of the arrows, illustrating a part of the ball-collecting pan and the ball-return runway.

Figure 7 is an enlarged, detail, sectional view through one of the tracks of the game board, illustrating one form of circuit closer for an electrical score board, which can be used with my device.

Figure 8 is a fragmentary top plan view of a slightly modified form of game board.

Figure 9 is a top plan view of a further modified form of my game board.

Figure 10 is a central vertical section taken on the line 10—10 of Figure 11, looking in the direction of the arrows, showing the hand ball game embodying certain principles of my invention.

Figure 11 is a top plan view of the hand ball game.

Referring to the drawings in detail, wherein similar reference characters designate corresponding parts throughout the several views, the letter G generally indicates my novel pinball game, and the same includes a cabinet or casing 15, which can be built in various manners, so as to present an attractive appearance to the eye.

As illustrated, the cabinet or casing 15 includes rear walls 16 and 17, side walls 18, and a bottom wall 19. The top of the casing is partially closed by a depending inwardly flexed top wall 20. This top wall 20 has formed on its inner edge a depending annular guard flange 21,

the purpose of which will be later set forth. Game balls 22, which can take the form of steel marbles, are adapted to be projected up through the center of the top wall 20. Hence, the top of the cabinet is closed by a transparent cover 23. This cover 23 can be made from any desired material, such as plastic, glass, or the like, and the cover can be fastened to the top of the cabinet in any appropriate way, such as by screws 24. These screws 24 can also be utilized for holding the top wall 20 in place.

The transparent cover 23 can consist of side walls 25 and an arcuate front wall 26. The rear edges of the walls 25 and 26 can be secured to an electric score board 27. This electric score board also performs the function of completing the cover. In view of the fact that the score board can be of the type commonly employed in pinball machines, the same will not be described or illustrated in detail, and the same forms no part of this invention per se.

Mounted within the cabinet or casing 15 is the game board 28, which can be formed from sheet metal or any other preferred material suitably colored and ornamented to create an attractive appearance. As illustrated in Figures 2 and 4, the game board 28 can include a plurality of stepped concentric tracks or runways 29, which progressively increase in size toward the bottom of the game board. The lowermost track or runway 29 carries an outstanding annular gutter 30, and this trough has formed on its periphery a marginal flange 31, which can be welded or otherwise secured to a guard collar 32. The guard collar 32 receives the guard flange 31 formed on the top wall 20, and the flange is arranged normally in spaced relation to said collar. Also rigidly secured to the collar 32 below the game board 28 is a ball-collecting pan 33. The pan is so formed as to receive the balls from the game board, and the pan is depressed at one point, so that the balls received thereon will all gravitate to such depressed point, irrespective of the tilting movement of the game board.

At the extreme low point of the pan, the same is provided with an outlet opening 35, and a downwardly inclined ball-receiving trough 36 is carried by the pan and receives the balls as the same drop through the opening. The trough 36 leads to an axially disposed ball-projecting barrel 37. The barrel is provided with an opening 38 through which the balls 22 from the trough are adapted to enter said barrel. The barrel extends through the axial center of the game board, and the balls are adapted to be projected up through the barrel onto said game board by means 39, which will be specifically described. The upper end of the barrel can be provided with spring guard fingers 40 to prevent the return of the balls into the barrel after the same have been shot. A spider 41 has its hub rigidly secured to the barrel, and the terminals of the arms of the spider are firmly secured to the game board. Hence, the game board, the ball-collecting pan 33, and the barrel 37 are all connected together as a single unit.

In the form of my game board shown in Figures 2 and 3, the gutter 30 thereof is provided with a row of openings 42, and as the balls drop from one track or runway 29 to the other, the same will finally reach the gutter and drop through the openings 42 into said pan 33.

The game board and its associate parts are mounted within the cabinet or casing 15 in a novel manner, so that the same can be rocked

in various directions. The means for mounting the game board can include an annular supporting ring 43, and this ring at diametrically opposite points carries pointed bearing screws 44.

5 The pointed bearing terminals of the screws are received in bearing blocks 45 secured to the side walls 18 of the casing or cabinet 15. Similar bearing screws 46 are also carried by the supporting ring 43, and these screws are arranged 10 diametrically opposite one another and equidistantly between the screws 44. The inner pointed terminals of the screws 46 are received in bearing blocks 47 rigidly secured to the guard collar 32. As the guard collar 32 is carried directly 15 by the game board, it can be seen that the game board can be rocked in any direction.

The means 39 for ejecting the balls 22 at different speeds from the barrel 37 includes a pistol-shaped casing 48 having a hand grip 49 on one end thereof. The casing 48 extends into the cabinet 15 through an enlarged opening 50 in the front wall thereof, and the forward end of the casing 48 is provided with a sleeve 51, which communicates with the lower end of the barrel 37 by means of a suitable opening formed in said barrel or a continuation of the ball opening 38. Slidably mounted within the sleeve 51 is an elongated longitudinally extending rod or firing pin 52. Fastened to the rod is a collar 53 against 20 which bears an expansion coil spring 54. The inner end of the spring bears against a partition wall 55 formed in said pistol-shaped casing 48. The casing is rigidly secured to the extreme lower end of the barrel 37 by means of a bracket 30 56, which projects radially from said barrel.

In order to hold the game board level, the lower end of the barrel 37 can carry a weight 57 on the opposite side thereof from the ball-shooting mechanism 39, and the weight can be adjusted 40 toward and away from said barrel.

Slidably mounted on the rod 52 in rear of the partition wall 55 is a trigger or spring loading device 58. This trigger or spring loading device 58 is normally urged toward the partition 55 forwardly on said rod 52 by an expansion spring 59. The trigger can be detachably latched to the rod by means of a latch plate 60, which is slidably mounted on said trigger. The rod has formed 45 therein a keeper notch 61 for receiving the latch plate 60 when the same is in a raised position. The upper end of the latch plate 60 is slidably mounted on a forwardly extending arm 62 formed 50 on or secured to the hammer or latch release device 63. This hammer is rockably mounted intermediate its ends on a pivot pin 64 carried by the pistol-like casing. A small tension spring 65 is connected to said hammer and casing for normally holding the hammer in a predetermined 55 position and the latch plate 60 in its raised latching position. The latch construction is shown to good advantage in Figure 5 of the drawings.

Pivottally mounted within the barrel 37 is a bell crank-shaped lever 66. One arm of the bell crank-shaped lever receives one ball at a time 65 from the trough 36, and the other arm of the bell crank-shaped lever is disposed in front of the rod or firing pin 52. Obviously, when the rod is projected forwardly under influence of the spring 54, the bell crank-shaped lever will be forcibly 70 actuated for projecting one ball 22 from the barrel 37. By compressing the spring 54 more or less, the balls can be projected with more or less force or speed, as may be desired by an operator or player.

75 From the description so far, it can be seen

that when the trigger 58 is latched to the rod 52, the rod can be brought back against the tension of the spring 54 a desired distance by the operator. When the trigger has been brought back to the desired selected point, then the rod can be released from the trigger by pushing inwardly on the upper end of the hammer 63. This will push the latch plate 60 downward away from the keeper notch 61. As soon as the latch plate moves away from the walls of the keeper notch, the rod will be forcibly urged toward the bell crank lever 66 and project a ball through the barrel and above the game board 28.

As the operator can change the position of the game board and the barrel 37, the operator or player can shoot the ball above the game board in a desired path, and in order to obtain high score, it is advantageous, as will be later set forth, for the ball to drop on the uppermost runway or track 29. After the ball is projected, the operator can still manipulate the pistol casing for tilting the game board in any desired direction to control the travel of the ball from one runway to the other within certain limits.

In order to prevent turning of the rod 52 within its sleeve 51, the rod can be provided with a keyway 65', and a set screw 66' is carried by the sleeve for engaging the walls of said keyway. This insures the proper alignment of the latch plate with the keeper notch 61.

As my game is to be played as an ordinary pinball machine, it is preferred to provide a coin-controlled mechanism for releasing a predetermined number of balls for play each time a coin is deposited in the machine. Consequently, a coin slide plate 67 can be provided, as is clearly shown in Figure 1 of the drawings. The coin control mechanism can be of any preferred character and forms no part of the present invention per se. However, when a coin is deposited, a circuit will be closed through a solenoid 68 (see Figure 2). This solenoid can be carried by one arm of the spider 41, and the plunger of the solenoid has connected therewith an operating rod 69, which is operatively connected to a pivoted gate 70. The gate controls the movement of a certain group of balls down the trough 36 to the barrel 37, and, obviously, when the solenoid is energized and the gate is raised, a certain number of balls can travel down the trough to the barrel.

As heretofore stated, any preferred type of electrical score board can be provided with my appliance, and suitable electrical switches are arranged at different points on my game board, so that each time a ball hits and throws a switch, a certain number of points will be counted and shown on said score board.

In Figure 4, I have shown each runway and gutter provided with four switches 71. While the switches can be of any preferred character, I have shown one preferred operating mechanism for the switches in Figure 7. Each switch is of a sensitive character and includes a circuit-closing switch lever 72 against which normally rests one arm of a trip lever 73. The trip lever is rockably mounted at one on a pivot pin 74 carried by the game board. It can be seen that as a ball rolls against the raised arm of the trip lever 73, the lever will be depressed for operating the switch. It is to be noted, however, that the ball, to operate a trip lever, must roll in one direction, for if a ball rolls in the reverse direction against the trip lever, the same will strike

the abrupt end of the trip lever, which will act as a stop therefor.

At a certain point on each track or runway and in the gutter is a baffle or stop plate 75. In order to make the highest possible score, the ball should take the path shown by the arrows in Figure 4. Consequently, a ball should land, first, on the uppermost runway or track and make a complete travel therearound until the same strikes the baffle plate 75. The ball should then drop to the next track or runway and travel around the same until it strikes the baffle plate on that track, and so on until the ball reaches the gutter and falls through one of the openings 30.

As heretofore intimated, the game board can take other forms, and in Figure 8, I have shown a game board 76. This game board 76 is substantially the same as the game board 28, the only difference being that each runway is provided with an opening 77 through which the ball can drop to the pan. Hence, the openings 77 constitute hazards.

In Figure 9, I have shown a still further form 25 of game board, and the same is generally indicated by the reference character 78. This game board 78 differs from the game board 28 in that I provide a continuous spiral runway 79 from the center of the game board to the gutter. The switches for the score are arranged in substantially the same manner as that shown in the game boards illustrated in Figures 4 and 8, and the balls, as projected, are adapted to travel from the top of the game board to the gutter.

The principles of my game can be advantageously used in a hand apparatus, and in Figures 10 and 11, I have shown such an apparatus, and the same is generally indicated by the reference character H. This hand game can include a pan 80, which can take any preferred form. As shown, the same is of a cylindrical shape, and, hence, includes a disc-shaped bottom wall 81 and an annular side wall 82. Arranged within the pan 80 are concentric partition walls 83 and 84, and these walls, with the side wall, form a central compartment 85, an intermediate compartment 86, and an outer compartment 87. Obviously, however, any number of partition plates can be utilized to provide any preferred number 50 of concentric compartments.

The partition plates are secured to the bottom wall 81 in any preferred way. Secured to the lower face of the bottom wall 81 at its center is a handle 88, and the handle is bored for the 55 reception of an ejecting plunger 89. The lower end of the plunger has fastened thereto a manipulating fingerpiece 90. The upper end of the plunger has secured thereto a head 91. A spring 92 of the expansion type is coiled about the 60 plunger 89, and one end of the spring engages the head 91, while the other end of the spring engages a part of the handle. The axial center of the pan has formed therein an opening 93 by means of which a ball 94, which is to be shot 65 in the air, can be placed on the head 91 of the plunger.

In use of this device, the ball 94 is placed on the plunger head. One hand of the user is placed about the handle 88, and the plunger is moved down against the tension of its spring 92 by exerting downward force on the fingerpiece 90. Upon release of the fingerpiece 90, the ball is shot in the air, and the player endeavors to catch the ball in the pan.

Each compartment is marked to indicate a cer-

tain number of points. Thus, if the ball is caught in the central compartment 85, the same may count 1,000 points for the player. If the ball is caught in the intermediate compartment 86, 500 points are counted for the player. If the ball is caught in the outer compartment 87, then 100 points are counted for the player.

The playing of the hand game, while simple, is highly amusing, and considerable skill is required on the part of the operator to catch the ball or marble 94 in the central compartment.

Various changes in details may be made, which do not depart from the spirit and scope of my claims, and what I claim as new is:

1. In a game apparatus, a cabinet casing, a wall arranged in said casing having an opening and said wall being provided with a depending annular guard flange, a game board disposed in

the cabinet, means supporting the board for tilting movement, means for tilting the board from the exterior of the casing, and a guard collar surrounding said board and carried thereby receiving the depending guard flange.

2. In a game apparatus, a cabinet casing, a wall in said cabinet casing having an annular depending guard flange, a circular game board mounted within said cabinet below said wall including a plurality of concentric stepped annular runways, means rockably supporting the game board in said cabinet, means for rocking said game board from the exterior of said cabinet, and an annular collar secured to the margin of the game board and surrounding said guard flange, said collar being normally spaced from the flange.

HERBERT W. HARRIS.
